UNITED STATES PATENT OFFICE

2,353,398

PORTABLE DECK

Gerald G. Greulich, Mount Lebanon, Pa., assignor to Carnegie-Illinois Steel Corporation, a corporation of New Jersey

Application August 5, 1943, Serial No. 497,498

6 Claims. (Cl. 94—13)

This invention relates to portable decks or mats which are adapted for rapid assembly and dismantling, and particularly, to an improved portable deck especially adaptable as a landing field or decking for airplane runways, or for paved areas for other vehicular traffic.

In my copending application, Serial No. 456,233, filed August 26, 1942, which is entitled "Portable deck," there is shown and described a deck or mat similar to that disclosed in the present application, but the present deck is deemed to be an improvement thereover. In my prior application, there is provided rectangular-shaped plates having interlocking means arranged along their adjacent longitudinally extending edges so as to effect an interlock between each of the plates along the sides thereof. While the interlocking means shown therein is extremely effective and satisfactory for locking together the plates at the sides thereof, there is not provided any means for connecting together the plates at the ends.

Due to lack of continuity between the abutting ends of adjacent plates or planks in such a deck, there is a tendency, if a wheel load is disposed on or near the end of any particular plate, for the center of that plate to be depressed; whereas the adjacent plates being unloaded remain in higher plane. With repeated usage of the deck, particularly where the planes run in a track, the offset between the ends of the plates at the joints becomes great enough so as to be objectionable, particularly on soft soil or an uneven terrain. It is therefore obvious that if a means were provided for interlocking the adjacent ends of the plates as well as the sides, there would be provided an additional measure of continuity which would eliminate undesirable differential elevations between the ends of the plates; and, at the same time, there would be provided a deck having a more uniform elevation of the surfaces of all component parts over the entire area of the runway, and it is to such an end-connecting means that the present invention relates.

Accordingly, it is the general object of the present invention to provide an improved portable deck made of metallic plates having cooperating means arranged on each of the plates adjacent the ends thereof for interconnecting the abutting ends of the same which will not interfere with the rapid laying of the deck.

It is another object of the invention to provide an improved portable deck made of metallic plates having end interlocking means carried thereby which is positioned below the upper surface of

the plates so as not to interfere with the vehicular traffic over the assembled deck.

It is a further object of this invention to provide an improved portable deck made of metallic plates having end interlocking means carried thereby which is positioned below the upper surface thereof and which can be manipulated from the upper or top side of the plates or deck so that any particular plate can be easily and quickly removed or replaced.

It is still another object of the present invention to provide an improved portable deck made of metallic plates having end interlocking means carried thereby which is simple, inexpensive, and compact in its construction, and at the same time, efficient and effective in its use.

Various other objects and advantages of this invention will be more apparent in the course of the following specification and will be particularly pointed out in the appended claims.

In the accompanying drawings there is shown, for the purpose of illustration, an embodiment which my invention may assume in practice.

In these drawings:

Figure 1 is a plan view of the portable deck or mat of my invention showing my improved end-connecting or interlocking means incorporated therewith;

Figure 2 is a plan view showing details of the preferred form of the interlocking means arranged along the side or longitudinally extending edges of each of the plates;

Figure 3 is a sectional view taken on line III—III of Figure 2;

Figure 4 is a plan view of the end portions of two adjacent plates of my portable deck showing the improved means of the present invention for connecting the ends of the plates together;

Figure 5 is a sectional view taken on line V—V of Figure 4;

Figure 6 is a sectional view taken on line VI—VI of Figure 4; and

Figure 7 is a sectional view taken on line VII—VII of Figure 4.

Referring more particularly to the drawings, the improved portable deck or mat of my invention comprises a plurality of rectangular-shaped metallic plates 2 which are laid side by side in rows with the plates of adjacent rows being staggered relative to each other in a manner similar to that in which brickwork is laid so as to provide a continuous unitary deck or mat as shown in Figure 1 of the drawings. Along one of the sides or longitudinally extending edges of each of

the plates 2, there is arranged a plurality of spaced apart lugs 3 which are preferably T-shaped and which extend outwardly and downwardly from the edge of the plate so as to be disposed angularly relative thereto. As more clearly shown in Figures 2 and 3 of the drawings, each of the lugs 3 consists of a shank or stem portion 4 and an enlarged head portion 5. Along the opposite side or longitudinally extending edge of each of the plates 2 and inwardly of the extreme edge thereof, there is arranged a plurality of similarly spaced apart openings or slots 6, which are shaped similarly to the lugs 3, but have slightly larger dimensions so as to provide a slightly larger portion 7 for receiving the head portion 5 of a lug, and a slightly larger stem portion 8 for receiving the shank or stem portion 4 thereof. The portion 7 of each of the openings adapted to receive the head portion of the lug is disposed preferably substantially in the plane of the plate, as shown in Figure 3, with the stem portion 8 adapted to receive the shank portion of the lug arranged downwardly and outwardly so as to be disposed angularly relative thereto. The lugs 3 of one plate are adapted to be inserted in the openings 6 of an adjacently disposed plate so as to effect an interlock therebetween in a manner hereinafter to be described.

On the inner side of at least some of the openings or slots 6, preferably every other one, as shown in Figures 1, 2, and 3 of the drawings, there is arranged preferably an outwardly and downwardly extending lip or lug portion 9, which projects into the area of the enlarged portion 7 of the opening or slot 6 for a purpose to be described.

In each of the plates 2, there is arranged, preferably a plurality of rows of openings or apertures 10 which are shown as being circular-shaped in the present instance. Around the edges of each of the apertures 10, there is disposed preferably an inwardly and downwardly extending flange portion 12 so as to converge toward the bottom thereof. The flange portions 12 are preferably struck up and formed from the material punched from the plate to form the circular-shaped openings 10. Between each of the rows of openings 10, there is formed in each of the plates, a downwardly extending U-shaped rib portion 13 which extends preferably throughout the length of the plate for strengthening the same.

According to the present invention, as shown more clearly in Figures 4 through 7 of the drawings, there is arranged on the bottom side of each of the plates 2 adjacent one end thereof and directly next to the bottom surface of the plate and each of the U-shaped rib portions 13 arranged therein, a latch member 14 preferably made of flat stock rolled metal having a hook-shaped portion 15 arranged on the outer end thereof and a shank portion 16 which is pivotally attached to the body portion of the plate preferably by means of a flattened-head countersunk rivet 17. There is arranged in each of the plates directly above each of the latch members 14 carried thereby, an elongated opening 18 preferably extending longitudinally of the plate for a purpose to be described. On the opposite end of each of the plates there is arranged in the side wall of each of the U-shaped rib portions 13 at a spaced distance from that end of the plate, a slotted opening 19 having its axis extending transversely of the plates and arranged directly below the bottom surface thereof. The

hook-shaped portions 15 of the latch members 14 disposed on any one of the plates are adapted to cooperate with the slotted openings 19 in the rib portions 13 of an adjacent plate in a manner hereinafter to be described.

The improved portable deck or mat of my invention is assembled in the following manner. The plates are preferably assembled from the center of the area upon which the deck is adapted to be disposed and outwardly in opposite directions therefrom. To start the laying of the plates, the heads 5 of the lugs 3 arranged along the edge of one of the plates are interlocked with the heads of the lugs of the adjacently disposed plate with the plates disposed in substantially a horizontal position on the ground. In order to hold the lugs in engagement with each other so as to prevent longitudinal movement of the plates relative to each other and the disengagement of the lugs, there is disposed around the shank portions 4 of the interlocked lugs 3, preferably a wire binding member, but it will be understood that any other suitable means may be provided for holding these lugs in interlocked relation. By starting the laying of the deck in such a manner, it will be seen that the edges of these plates which are disposed in substantially the center of the area will have their openings or slots 6 disposed to each side thereof and will be free to receive the lugs 3 of the plate to be assembled and adjacently disposed in each direction from the center plates.

The succeeding plates are assembled into position in the following manner in each direction from these center plates. The plate to be positioned is disposed at an angle with the horizontal, with such angle being between approximately 40° and 100°. The head portions 5 of each of the lugs 3 along the edges of the plate are then inserted into the enlarged part 7 of the openings 6 arranged along the edge of the horizontally disposed center plate which has already been laid in position on the ground. After the heads 5 of the lugs have been inserted in their respective openings 6, that plate is moved to a substantially horizontal position and to the position it will assume upon the ground. The remaining plates of the deck are assembled in a similar manner until the desired size deck is obtained.

Upon movement of the plates to their substantially horizontal position after the lugs 3 have been inserted in the openings 6, it will be seen that the shank or stem portions 4 of the lugs move downwardly into place and rest in the enlarged stem portions 8 of their respective openings due to the angular arrangement thereof, as shown in Figure 3. In such position it will be seen that the lugs 3 are disposed in the openings 6 beneath the bottom of the adjacently disposed plate, with the inner edges of the lugs being disposed beneath the outer edges of the enlarged part 7 of the openings 6. In other words, the stem portions of the slots permit the neck behind the projecting head of the adjacent plate to enter and lie below the top surface of the deck. It will be seen that the component or vertical edge or edges on either side of the slots restrain the inner sides or edges of the projecting heads from sidewise movement or disengagement and they also restrain the necks from lengthwise movement. It will be understood that each of the slots or openings 6 has enough of its area in a horizontal plane to accommodate and permit entry of the head portion of the lugs. Also, if desired, the depth of the enlarged portion 7 of

each of the openings may be just slightly greater than the thickness of the head of the lugs so as to permit entry of the lugs only when they are disposed substantially perpendicular thereto or in a vertical plane. In such an arrangement the outer edges of the lugs would be disposed beneath the inner edges of the openings or slots 6 when the plates are moved to a horizontal position thereby preventing vertical movement of the lugs through the openings.

The outwardly projecting lip portions 9 which extend over the heads of the lugs after assembling are provided so as to prevent the vertical movement of the heads 5 of the lugs 3 from their position below the plate and through the openings 6. In other words, the head portions 5 of the lugs 3, do not extend in under the edges of the slots 7 but are maintained in place vertically solely by the lip portions 9. Such a construction possesses the advantages that any particular plate in the deck may be removed in case of damage for repairs or replacement without moving or disturbing the remainder of the plates therearound. If it is desired at any time to remove any particular plate from the deck, the projecting lugs or lip portions 9 are bent downwardly or upwardly as desired, as shown in the broken lines of Figure 3 of the drawings, so as to permit the passage of the heads 5 of the lugs 3 up through the enlarged portions 7 of the openings 6 with little or no pivoting movement. The new plate to be assembled therein is engaged with the adjacent plate, in a manner hereinbefore described, and moved to its horizontal position with the lugs thereof positioned in the openings of the adjacent plate. After such plate has been moved to its horizontal position, the lugs 9 are again bent outwardly and upwardly, or inwardly and downwardly, as the case may be, as shown in the full lines of Figure 3, so as to prevent upward movement of the heads of the lugs through the openings with the lip portion performing its original function of locking the projecting head in position.

The end-connecting means of the present invention for interlocking the abutting ends of the plates are manipulated in the following manner. After the plates have been assembled in the manner described with the side or longitudinally extending abutting edges interconnected so as to provide a deck of the desired size, it will be seen that the ends of adjacent plates are spaced a slight distance from each other, as shown in Figures 1 and 4 of the drawings. In order to move each of the latch members 14 into engagement with the respective slotted openings 19, a suitable tool is inserted into the elongated opening 18 arranged in the plates above each of the latch members. The tool is manipulated so as to engage the shank portion 16 of the latch member so as to move the hook-shaped portion 15 thereof outwardly toward the end of the plate, as shown in Figure 4 of the drawings. After the latch member has been moved so as to extend across the opening between the abutting ends of the plates, the tool is then inserted in the space between the abutting ends and the latch member moved until the hook-shaped portion 15 carried thereby passes through the respective slotted opening 19 in the side wall of the rib portion 13 so as to engage therewith. After all of the latch members have been moved to their locked position in the manner described, it will be seen that the abutting ends of all of the plates are interlocked so as to prevent movement thereof

relative to each other. The latch members may be moved to unlocked position by inserting and moving said tool in the space between the ends of the plates.

As a result of my invention, it will be seen that there is provided a device for locking the ends of the plates together which can be manipulated from the top or upper side of the plates or deck either to unlock or to lock the same, and which will not interfere with the rapid initial laying and side locking of the deck. It will also be seen that there is provided an end-locking arrangement which will not interfere with the stacking of the plates during storing or shipping which is one of the most important aspects of the present invention.

While I have shown and described one specific embodiment of my invention, it will be understood that this embodiment is merely for the purpose of illustration and description and that various other forms may be devised within the scope of my invention, as defined in the appended claims.

I claim:

- 25 1. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a hook receiving portion arranged on the opposite end of each of them whereby the hook member on the end of any one plate is adapted to cooperate with a hook receiving portion of an adjacent plate disposed at that end thereof whereby the ends of the plates are securely locked together so as to prevent movement thereof relative to each other.
- 30 2. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a hook receiving portion arranged on the opposite end of each of them whereby the hook member on the end of any one plate is adapted to cooperate with a hook receiving portion of an adjacent plate disposed at that end thereof whereby the ends of the plates are securely locked together so as to prevent movement thereof relative to each other.
- 35 3. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 40 4. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 45 5. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 50 6. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 55 7. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 60 8. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 65 9. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 70 10. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.
- 75 11. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly extending rib portion formed in the opposite end of each of said plates having an opening arranged therethrough substantially parallel to the plane of the plate and positioned at a spaced distance from the end thereof, said hook member on the end of any one of said plates adapted to cooperate with the opening through the rib of an adjacent plate disposed at the end thereof whereby the ends of the plates are securely locked together so as to prevent movement thereof relative to each other.

extending edges of each of said plates for connecting the same to adjacent plates disposed to either side thereof, and a plurality of hook members mounted on the bottom side of each of said plates adjacent one end thereof and arranged for pivotal movement in a plane substantially parallel thereto, each of said ribs having an opening arranged in the side wall thereof at a spaced distance from the end of the plate on the end opposite that from said hook members, said hook members on the end of any one of said plates adapted to cooperate with the respective openings in the ribs of an adjacent plate disposed at the end thereof whereby the ends of the plates are securely locked together so as to prevent movement thereof relative to each other.

4. A portable deck of the class described, as defined in claim 3, wherein each of the plates has an opening arranged therethrough adjacent each of the hook members carried thereby so that the same may be manipulated through said openings whereby the hook members can be moved to their locked position.

5. A portable deck of the class described, as defined in claim 3, wherein each of the hook members consists of a flat metallic member having a hook-shaped portion arranged on the outer end thereof which is adapted to engage with a slotted opening in the side walls of the respective ribs,

with the inner end of each of the hook members being pivotally attached to the body of the plate by means of a rivet so that the hook members are positioned directly next to the bottom surface of the plate and to one side of the ribs formed therein.

6. A portable deck of the class described comprising a plurality of metallic plates for rapid attachment to and detachment from each other, each of said plates consisting of a substantially rectangular-shaped body portion of rolled metal, means arranged along the longitudinally extending edges of each of said plates for connecting the same to adjacent plates disposed to either side thereof, at least one hook member mounted on the bottom side of each of said plates adjacent one end thereof and arranged for pivotal movement in a plane substantially parallel thereto, and a downwardly depending portion carried by each of said plates adjacent the opposite end thereof having an opening arranged therein, said hook member on the end of any one of said plates adapted to cooperate with the opening in the depending portion of an adjacent plate disposed at the end thereof whereby the ends of the plates are securely locked together so as to prevent movement thereof relative to each other.

GERALD G. GREULICH.
